UNITED STATES PATENT OFFICE.

ALBERT D. JEFFREY, OF BROOKLYN, NEW YORK, ASSIGNOR OF ONE HALF
TO WILLIAM SANDERSON, OF SAME PLACE.

MECHANICAL MOVEMENT.

SPECIFICATION forming part of Letters Patent No. 339,893, dated April 13, 1886.

Application filed September 16, 1885. Serial No. 177,297. (No model.)

To all whom it may concern:

Be it known that I, ALBERT D. JEFFREY, a citizen of the United States, residing in the city of Brooklyn, in the county of Kings and State of New York, have invented a certain new and useful Improvement in Mechanical Movements, of which the following is a specification.

This invention relates to mechanism for the transmission of continuous rotary motion from one shaft to another, the object being to provide a means of multiplying the speed with less loss of power through friction than when gearing is used.

15 The distinguishing feature of my improved movement is the combination of a crank or cranks on the driven shaft, a cam or cams on the driving-shaft having a cycloidal groove or slot, and a connecting-rod jointed at one end to the crank, and terminating at the other end in a roller which travels in said groove or slot, being suitably guided so as to restrain its movement to a direction toward and from the axis of the driven shaft.

25 Figure 1 of the accompanying drawings is a front elevation of my improved movement. Fig. 2 is a vertical section (on the line 2 2 in Fig. 3) showing one cam, crank, and connecting-rod. Fig. 3 is a plan of the movement, 30 and Fig. 4 is a view answering to Fig. 2, and showing a modification.

Let A designate the driving-shaft, and B the driven shaft. On the driving-shaft are fixed two cam-disks, C C, and on the driven shaft are two cranks, D D.

35 E E are two connecting-rods or pitmen, each jointed at one end to one of the cranks, and bearing on its other end a roller, e. This roller enters a groove or slot, c, in the corresponding cam C. This slot is just sufficiently wide to receive the roller freely, without allowing it any lost motion or play between the sides of the slot. The slot c is cycloidal, its axis (indicated by dotted line x in Fig. 2) being a 45 cycloidal curve, such as would be generated by a pendulous reciprocation executed during a uniform rotation of the cam-disk and in a direction toward and from its center.

The slots in the cams shown in Figs. 1, 2, 50 and 3 represent two complete reciprocations to one revolution, while that shown in Fig. 4

represents three complete reciprocations to a revolution. The mechanism shown in the former figures is designed for transmitting to the driven shaft twice the speed of the driver, 55 while that shown in the latter figure is designed for transmitting to the driven shaft three times the speed of the driver.

Each roller e, or the end of the connecting-rod bearing the roller, is so mounted or guided 60 that it can move only in a direction toward and from the center of the driving-shaft, and substantially in a straight line extending between the axes of the two shafts. The preferable way of thus guiding the roller is to suspend it by a pendulous arm, F, from a fixed point, f, overhead, as shown most clearly in Fig. 2.

One of the cranks D D is set on the shaft B ninety degrees, or one-fourth of a revolution, 70 in advance of the other, and the corresponding one of the cams C C is set on the shaft A forty-five degrees, or one-fourth of a half-revolution, in advance of the other, as shown in Fig. 1.

75 The operation is obvious. As the shaft A revolves with its cams, the sinuous slot c in each cam forces the roller e (swinging from the center f) to reciprocate, and its motion is transmitted through the rod E to the crank D, which 80 it drives, the crank executing two revolutions to each revolution of the cam. By reason of one set of cams and cranks being set in advance of the other, as just described, the two cams and cranks work alternately, each being 85 at its phase of maximum advantage while the other is passing the dead-point. The motion is very smooth and free, the shaft B being driven with the minimum of friction.

My invention is adaptable to various uses, 90 such as the speeding-up of sewing-machines, the driving of velocipedes, the transmission of multiplied motion from the axle of a bar-vester to the cutter-bar shaft, &c.

The cams shown in Figs. 1 to 3 are two-throw 95 cams and transmit double speed. If three-throw cams are used, the transmission will be to triple speed. Four throw cams will give a fourfold speed, and so on, any desired multiplication of speed being attained by suitably 100 forming the cams.

It is not essential that two cams and two

cranks be used, the only object of duplicating them being to avoid dead-centers. If the driven shaft be provided with a fly-wheel, a single cam, connecting-bar, and crank will 5 usually suffice; but even then two are preferable.

I have herein referred to the shaft B as the "driven shaft," but with the duplicate arrangement of cams and cranks shown in Fig. 10 1 the power may be applied to this shaft and transmitted at a reduced speed to the shaft A.

The cams C C may be constructed in any way desired. Those shown consist of a disk 15 cut through to form the slot c, and the outer ring thus formed held in place by means of a diametrically-arranged bar, d, formed preferably in one piece with the cam-disk. It is not essential, however, that the cam shall consist of a disk, as any form of cam having a 20 cycloidal slot, groove, or other working-surface, acting in connection with a roller, connecting-rod, and crank, will come within my invention.

Fig. 4 shows a three-throw cam for transmitting motion at three times the speed of the driving-shaft. When two cranks and two cams are used, the cams should be set one thirty degrees in advance of the other, with cranks set ninety degrees apart. This view 30 also shows a modified means of guiding the roller e, a sliding block or head being arranged at the end of the rod E, moving in a

slideway, F. Any other suitable guide may be used.

I claim as my invention—

1. The combination, as a mechanism for transmitting multiplied rotary motion, of a driving-shaft, a cam thereon having a cycloidal slot or working face, a roller engaged and reciprocated thereby, a driven shaft with a 40 crank thereon, and a connecting-rod for communicating the motion of said roller to said crank, substantially as set forth.

2. The combination of a driving-shaft, two cams fixed thereon, one in advance of the other, and each having a cycloidal slot or equivalent working-face, two rollers engaged and reciprocated by the respective cams, the driven shaft with two cranks thereon, one set a quarter-revolution in advance of the other, two connecting-rods, each communicating the motion of one of said rollers to the corresponding one of said cranks, and guides for said rollers restraining them to move in a direction toward and from the driven shaft, substantially as set forth. 50 55

In witness whereof I have hereunto signed my name in the presence of two subscribing witnesses.

ALBERT D. JEFFREY.
